UNITED STATES PATENT OFFICE

2,669,970

FOUNTAIN PEN

Anthony Gordon, New York, N. Y.

Application May 3, 1950, Serial No. 159,698

2 Claims. (Cl. 120—51)

1

This invention relates generally to pens and more particularly to adjustable point writing pen construction.

It is among the objects of the present invention to provide novel pen construction in which the width of the written line, the flexibility of the pen point and the ink flow may be adjustably controlled.

Another object herein lies in the provision of structure of the class described having an ink reservoir and simple and effective means for filling the reservoir.

A further object herein is the provision of adjustable point, fountain pen structure which is simple and efficient affording a strong device so as to require a minimum of servicing.

These objects and other incidental ends and advantages will be more fully apparent during the course of the following disclosure, and be pointed out in the appended drawings.

In the drawings, to which reference will be made in this specification, similar reference characters have been employed to designate corresponding parts throughout the several views.

Figure 1 is a longitudinal sectional view of an embodiment of the invention with the point element in a retracted position thereof.

Figure 2 is a longitudinal sectional view corresponding to Figure 1 but showing the pen point element in an advanced position thereof.

Figure 3 is a vertical sectional view on the plane 3—3 on Figure 2.

Figure 4 is a fragmentary perspective view of a portion of the structure of Figure 3.

Figure 5 is a fragmentary perspective view of the compression means.

Figure 6 is an exploded view of the pen point element, the valve feed element and the hood element.

Figure 7 is a fragmentary plan view of the front end of the pen as set for a wide line (7—7 on Figure 1).

Figure 8 is a fragmentary plan view corresponding to Figure 7 of the pen as set for a narrow line (8—8 on Figure 2).

Figure 9 is a sectional view as seen from the plane 9—9 on Figure 2.

Figure 10 is a sectional view on the plane 10—10 on Figure 7.

In accordance with the invention the pen generally indicated by reference character 10 comprises generally: a first or inner barrel element 12; a second or outer barrel element 14; a casting element 16; a union element; a reservoir or sac 20; an adjuster element 22; a pen point ele-

2

ment 24; a valve element 26, and a hood element 28.

The first or inner barrel element is preferably tubular in shape, thin and strong. I have found metal tubing suitable, and it is provided in the upper portion with an elongated opening 31 at the ends of which is a pair of notch seats 32 and 33 (Figure 5), in the lower portion with an elongated slot 34; and at the rear end 36 with an internal annular flange 37.

The union element is of substantially standard type construction known in the pen art and has a generally cylindrical body 40, an ink channel element 41, an irregularly shaped external annular flange 42, a reduced portion 43 (upon which the sac 20 is hermetically attached), and a pen point element supporting platform 44. As shown in the drawing, the union element is composed of two parts, the cylindrical body 40 and the ink channel element 41 having the pen point element supporting platform 44 and rearwardly thereof the groove or channel 45.

The forward end of the inner barrel element is mounted upon the flange 42 preferably as a force frictional fit and the forward end 13 of the inner barrel element 12 secures the rear end 46 of the pen point element 24 upon the union element 40 by compressing the rear end 47 of the valve element 26 thereagainst. Surrounding the forward end of the inner barrel element 12 is a coupling element 15 which has at its rear end 48 internal threads which are engaged by corresponding threads on the front end 49 of the outer barrel element 14.

The second or outer barrel element 14 is of generally tubular shape and has an effective internal diameter or cross sectional area slightly greater than the external diameter or cross sectional area of the inner barrel element 12 so that the barrel element 12 may be slidable longitudinally therein. The rear end 50 of the outer barrel element 14 is internally threaded and is threadedly engaged by the adjuster element 22. The forward end 51 of the adjuster element 22 is provided with an annular groove 52 within which the flange 37 is slidably engaged. Rotation of the adjuster element 22 therefore affects axial displacement of the first and second barrel elements with respect to each other. The adjuster element 22 has a peripheral flange 53 which is a sliding fit within the casing element 16.

The bottom wall portion 54 is provided with a pair of spaced and parallel slots 55 and 56 forming a web 57 which is deformed up into the slot 34 to permit longitudinal movement of the

barrel element 12 and to prevent rotation thereof with respect to barrel element 14. The upper wall portion 58 of the outer barrel element 14 is provided with a plurality of openings 59 through which the fingers of the user may be inserted to engage the compressor 60. The compressor 60 is preferably curved so that it substantially fills the opening 31 and has a pair of projections 61 and 62 which when disposed in the seats 32 and 33 provide for pivotal movement about an axis extending through said seats.

The casing element 16 may be cylindrical and internally threaded at the forward end 63 to engage the front end 49 of the outer barrel element 14. The rear end 64 of the casing element 16 is internally threaded to receive the rear cap 65 which covers the handle portion of the adjuster element 22.

The pen point element 24 may be generally of standard construction with the exception that the nib members 66 and 67 are normally spaced from each other a substantial distance by a capillary slit 68, said slit extending a greater distance than the normal distance toward the rear end 46. As seen in Figure 6 the inner end 69 of the slit 68 extends a substantial distance inwardly beyond the ink receiving indentations 70 and 71. The indentations 70 and 71 are elongated so that when the nibs 66 and 67 are forced together an elongated opening for the passage of ink is provided. The outer edges of the nib members 66 and 67 are curved to provide cam surfaces 72 and 73.

The valve element 26 includes a mounting member 74 which when the pen 10 is assembled surrounds the rear end 46 and embraces the union element. The forward portion of the valve element 26 includes a valve plate 27 which is flexible and resilient and which is arcuately upwardly curved to present a concavity at the under surface 29 thereof superposing the slit 68 and the indentations 70 and 71. The downwardly curved tip 75 is adapted to rest upon the forward upper surfaces of the nib members 66 and 67.

The hood element 28 may have a frusto-conical shape and is secured upon the front end 49 of the outer barrel element 14, either by the threads as shown or this may be a force fit. The hood element 28 has a pair of oppositely disposed downwardly projecting cam followers 78 and 79 which are adapted to coat with the cam surfaces 72 and 73 as will more fully appear. The inner surface 80 of the upper portion 81 of the hood element 28 forms a cam which coats with the convex upper surface of the valve plate 27.

Operation

The pen point element 24 normally gets ink from the sac 20 through the groove or channel 45. Assuming the pen 10 to be set to write a fine line, the pen point element is thus advanced so that the cam followers 78 and 79 on the hood element 28 squeeze the pen slit 68 practically closed. Ink consumption is relatively low. The space lying above the pen point element and below the valve plate 27 is relatively shallow because the inner surface of the hood has pressed the valve plate 27 against the top of the pen point element; then the capillary attraction is greater than the force of gravity and ink flow is only enough to replenish what has been consumed by writing or evaporation from the exposed point. Now if it is desired to change to a broad line, the pen point element 24 is retracted by turning the element 22, and the slit widens by

springing open. If writing is immediately commenced the demand for ink volume is instantly relatively much greater. While the widened slit 68 of the pen point element 24 can carry more ink an additional path for ink is provided by the increased space between the under surface of the valve plate 27 which acts as an ink regulator and the upper surface of the pen point element 24. Even if the slit 68 of the pen point element 24 gets too wide so that capillarity is broken, then the valve plate 27 forms a channel to assure ample ink delivery for application to the surface being written upon.

The movement of the pen point nib members 66 and 67 and the movement of the valve plate 27 are slightly exaggerated in the drawings for purposes for clarity and the spaces between the parts carrying ink in order to maintain proper capillary action will be affected by the viscosity of the ink 100.

Operation of the present device is therefore a simple and convenient matter. When it is desired to replenish the sac 20 the casing 16 is removed at the threads at the front indicated by reference character 49. This exposes the openings 59 where digital pressure may actuate the compressor 60 to produce suction in the sac 20. After filling the casing is replaced. When it is desired to change the width of the line drawn by the pen point element, the adjuster element 22 is rotated, to retract the pen point element 24 when a wider line and more flexible action is desired or rotated in the opposite direction to move the cam surfaces 72 and 73 forward so that the followers 78 and 79 close the slit as seen in Figure 8. Intermediate positions may be used, the parts being held by friction. The valve element 26 moves with the pen point element and is acted upon by the cam surface on the hood element.

I wish it to be understood that I do not desire to be limited to the exact details shown and described in this specification, for obvious modifications will occur to a person skilled in the art to which the present invention pertains.

I claim:

1. Fountain pen construction comprising: a pen point element, a hood element, and a resilient valve element; said pen point element having an opening and an adjustable slit communicating with said opening, to form pen point nib members; said valve element being positioned to overlie said opening in said pen point element; said hood element at least partially overlying said pen point element and valve element, and having a cam surface engageable with said valve element; said hood element also having a pair of downwardly extending cam elements engageable with the outer edges of said nib members whereby relative movement between said pen point and valve element, and said hood element, in one direction simultaneously cams the nib members closer together and cams said valve element upon said opening in said pen point element; and in an opposed direction permits the nib members to spring further apart, and the valve element to spring to a position above and spaced from said opening in said pen point element.

2. Fountain pen construction comprising: a pen point element, a hood element, and a resilient valve element; said pen point element having an opening and an adjustable slit communicating with said opening, to form pen point nib members; said valve element being positioned to overlie said opening in said pen point element;

said hood element at least partially overlying said pen point element and valve element, and having a forwardly and downwardly sloping surface engageable with said valve element; said hood element also having a pair of downwardly extending cam elements engageable with the outer edges of said nib members whereby relative movement between said pen point and valve element, and said hood element, in one direction simultaneously cams the nib members closer together and cams said valve element upon said opening in said pen point element; and in an opposed direction permits the nib members to spring further apart, and the valve element to spring to a position above and spaced from said opening in said pen point element.
